US0D1070824S

(12) **United States Design Patent** (10) **Patent No.:** **US D1,070,824 S**
(45) **Date of Patent:** **** Apr. 15, 2025**

(54) **WIRELESS MICROPHONE**

(71) Applicants: **GUANGZHOU SHIYUAN ELECTRONIC TECHNOLOGY COMPANY LIMITED**, Guangzhou (CN); **GUANGZHOU SHIRUI ELECTRONICS CO., LTD.**, Guangzhou (CN)

(72) Inventor: **Cheng Zhang**, Guangzhou (CN)

(73) Assignees: **GUANGZHOU SHIYUAN ELECTRONIC TECHNOLOGY COMPANY LIMITED**, Guangzhou (CN); **GUANGZHOU SHIRUI ELECTRONICS CO., LTD.**, Guangzhou (CN)

(**) Term: **15 Years**

(21) Appl. No.: **29/891,064**

(22) Filed: **May 1, 2023**

(51) LOC (15) Cl. **14-01**

(52) U.S. Cl.

USPC **D14/225**; D14/205

(57) **CLAIM**

The ornamental design for a wireless microphone as shown and described.

DESCRIPTION

FIG. 1 is a left front perspective view of a wireless microphone showing the claimed new design;

FIG. 2 is a right front perspective view thereof;

FIG. 3 is a front view thereof;

FIG. 4 is a rear view thereof;

FIG. 5 is a left-side view thereof;

FIG. 6 is a right-side view thereof;

FIG. 7 is a top view thereof;

FIG. 8 is a bottom view thereof;

FIG. 9 is a partially enlarged view of a left bottom region in FIG. 1;

FIG. 10 is a partially enlarged view of a left bottom region in FIG. 2;

FIG. 11 is a partially enlarged view of a right bottom region in FIG. 4;

(Continued)

FIG. 12 is a partially enlarged view of a bottom region in FIG. 5; and, FIG. 13 is a partially enlarged view of a left region in FIG. 8.

The broken lines in the drawings depict portions of the wireless microphone that form no part of the claimed design.

1 Claim, 13 Drawing Sheets
